UNITED STATES PATENT OFFICE

OSCAR R. HANKINS, OF AURORA, ILLINOIS, AND JOACHIM R. M. KNUDSEN, OF MUSKEGON, MICHIGAN; SAID HANKINS ASSIGNEE TO SAID KNUDSEN

WINDOW SASH AND CASING

Application filed January 14, 1929. Serial No. 332,448.

This invention relates to a metal window construction and is directed to a particularly simple economically constructed and efficient window, including an outer frame or casing for the window with a window each mounted therein which may be located either in completely closed position, in an outwardly inclined position or in one of a large number of upper inclined positions in which it will be 5 securely held.

The construction of the window is fully described in the following description taken in connection with the accompanying drawing, in which,

Fig. 1 is an elevation of the window, certain parts being broken away and shown in section for better disclosure of the construction.

Fig. 2 is a vertical section through the construction shown in Fig. 1 and with the window sash in one of its upper inclined positions, and

Fig. 3 is a fragmentary enlarged horizontal section substantially on the plane of line 3—3 of Fig. 1, looking downwardly as indicated by the arrows.

Like reference characters refer to like parts in the different figures of the drawing.

The outer frame or casing of the window is of sheet metal and includes two vertical ends 30 and upper and lower sides. Each of the ends is of Z-bar form having a web 1, an inwardly turned flange 2 at one edge of the web and an outwardly turned flange 3 at the other edge of the web and at the outer or front side of the window.

The upper side of the window frame is of sheet metal and includes an outer or front vertical flange 4 from which a web section is bent to the rear at right angles for a distance, 40 as indicated at 5, then turned downwardly to make a vertical ledge 6, and thence again to the rear making a horizontal section 7 which at its rear edge is turned upwardly at right angles to make the vertical flange 8, the upper edge of which is positioned in substantially the same horizontal plane as the upper edge of the flange 4.

The lower side of the frame includes an outer vertical flange 9, a horizontal web section 10 turned inwardly at right angles for

a distance thence downwardly making the vertical ledge 11 and then again horizontally to the rear making the section 12 which terminates in a downturned flange 13, the lower edge of which is in the same horizontal plane with the lower edge of the flange 9. The two ends and the upper and lower sides of the frame are permanently secured at the corners of the frame preferably by welding.

At the inner side of the web 1 of each of the ends of the frame, a plate 14 of sheet metal is positioned and permanently secured, as by spot welding, at its lower end and near its rear edge being pressed inwardly to form the projecting portion 14^a, at its forward edge having an inturned flange 15 which is inclined slightly to the vertical and which for a portion of its intermediate length is provided with a series of spaced apart rearwardly extending projections 16 thereby providing, directly opposite said projections, recesses 16^a in the front side of the flange which recesses are spaced short distances apart as shown.

The window sash is also of sheet metal having two spaced vertical ends and upper and lower sides. The ends are of Z-bar form including each a web 17, an inwardly turned rear flange 18 and an outwardly turned front flange 19 which is adapted to lie in front of the adjacent flange 15 previously described. Near the lower end and at the outer side of each web 17 a pin 20 is permanently secured extending therefrom toward the adjacent plate 14.

The lower side of the window sash is likewise of Z-bar form having horizontal web 20, a downwardly extending rear flange 22 and an upwardly extending front flange 23. The upper side of the window sash is of angle form including the horizontal leg 24 from which a shorter downwardly extending leg or flange 25 is bent; it together with the flange 22 previously described being in the same plane with the flanges 18 of the Z-bar ends. These members making the outer frame of the window sash are welded at the corners of the sash to make a rigid and permanent construction.

The window sash carries glass panes 26 which come against the flanges 18 and 25 and

if the length of the sash is to be divided so as to carry more than one pane of glass any suitable vertical dividing partition 29 may be used for such purpose and the glass may be held in place by any suitable retaining means indicated at 27. The window sash at its upper side is equipped with the usual releasable catch 28 the structure of which is no part of the present invention.

In the assembly of the window frame or casing and the window sash the pins 20 lie back of the flanges 15 and in the lower position of the sash in front of the projection 14^a whereby the sash is held securely against undesired movement thus eliminating rattle or other noises. The flanges 19 of the sash are in front of said flanges 15. When the window is in closed position, flange 22 lies back of the ledge 10 and the flanges 19 bear against the flanges 15 described. The lower front edges of the webs 17 are preferably rounded so that the window may be tilted to the dotted line position shown in Fig. 2, the pins 20 bearing against the flanges 15 and the flange 22 of the window sash contacting against the flanges 2 of the Z-bar ends of the window frame.

The window may also be elevated, as shown in Fig. 2, and may be held in any one of a number of different positions with the lower edges of the flanges 19 seating in horizontally opposed recesses 16^a while the pins 20 are disposed at the rear sides of the flanges 15 between two of the projections 16. The window sash accordingly may be raised to any number of different positions depending upon the number of recesses 16^a used in the flanges 15.

This construction of window is relatively simple and economical to produce, the cost of manufacturing being low because of the simplicity of the construction and the minimum number of parts used. The ability to adjust the window to the many different positions described is a feature of considerable value. The invention is defined in the appended claims and is to be considered comprehensive of all forms of structure coming within their scope.

We claim:

1. In a construction of the class described, an outer casing of metal having vertical ends and upper and lower sides, a metal plate secured to the inner side of each of said ends, each of said plates having an inturned flange, a window sash located in said frame having vertical ends and upper and lower sides of metal, each of said vertical sides having an outturned flange located at the front of the inturned flange of the adjacent metal plate and lying within the ends of said casing and pins projecting one from each end of the window sash located back of said flanges on said plates.

2. A window construction comprising, a

window casing of metal having vertical ends and upper and lower sides connected together at the corners of the casing, a metal plate permanently secured at the inner side of each of said ends of the casing having an inturned flange at its front edge, each of said flanges for a portion of its length being formed with spaced apart rearwardly extending projections opposite which are formed depressions in the front sides of said flanges, a window sash of metal located within said casing having vertical ends and upper and lower sides, each of said vertical sides having an outturned flange to lie in front of the inturned flange of the adjacent plate, and pins projecting from the ends of said window sash near the lower end portions thereof located back of said flanges of said plates, whereby the window sash may be elevated to various positions and turned outwardly at its upper end, the lower edges of the flanges on the ends of said sash seating in depressions in the flanges of said plates and the said pins bearing against the rear sides of the flanges of said plates between projections thereon.

3. A metal window comprising, an open metal casing, a metal sash located within the casing, each of the ends of said sash having an outturned flange at the front thereof and each of the ends of the casing having an inturned flange between its front and rear sides, said flanges on the sash being adapted, in the closed position of the window, to lie within said casing and in front of said flanges on the ends of the casing, and means projecting from the ends of the sash near the lower portions thereof and lying back of said flanges on the ends of the casing.

4. A window comprising, an open casing having vertical ends and upper and lower sides of metal, said upper side including front and rear horizontal sections connected by a vertical ledge, the rear section being in a lower plane than the front section, and said lower side comprising two horizontal sections connected by a vertical ledge with the front section in a higher vertical plane than the rear section, a metal plate secured at the inner side of each end of the casing, at its front edge having an inturned flange, said flanges being located in front of said ledges, a window sash located inside of the casing including vertical ends and upper and lower sides of metal, the lower side being of Z-bar form and having a downwardly extending flange at the rear adapted to come back of the vertical ledge in the lower side of the casing, each of the ends of the sash having an outturned flange located in front of the flange of the adjacent plate on the ends of said casing, and horizontal pins projecting from the ends of the sash near the lower portions thereof back of said flanges of said plates.

5. A construction containing the elements in combination defined in claim 4, said in-

turned flanges of said plates between their upper and lower ends being formed with a plurality of spaced apart rearwardly extending projections located in a vertical series one over the other at the rear sides of said flanges and with depressions in the front side of said flanges opposite said projections, for the purposes described.

6. In a construction of the class described, an outer casing of metal having vertical ends and upper and lower sides, a metal plate secured to the inner side of each of said ends, each of said plates having an inturned flange, at one edge and an inwardly projecting portion adjacent its other edge and at its lower end, a window sash located in said frame having vertical ends and upper and lower sides of metal, each of said vertical sides having an outturned flange located at the front of the inturned flange of the adjacent metal plate and lying within the ends of said casing and pins projecting one from each end of the window sash located back of said flanges on said plates and adapted in the lower position of the sash to come between said flanges and inwardly projecting portions of said plates.

In testimony whereof we affix our signatures.

OSCAR R. HANKINS.
JOACHIM R. M. KNUDSEN.
